UNITED STATES PATENT OFFICE.

HARRY S. HART, OF CHICAGO, ILLINOIS.

DUMP-CAR-DOOR-OPERATING MECHANISM.

1,400,544.

Specification of Letters Patent. Patented Dec. 20, 1921.

Application filed September 21, 1918. Serial No. 255,025.

To all whom it may concern:

Be it known that I, HARRY S. HART, a citizen of the United States, residing at Chicago, in the county of Cook and State 5 of Illinois, have invented certain new and useful Improvements in Dump-Car-Door-Operating Mechanism, of which the following is a specification.

This invention relates to operating mechanism for dump car doors.

The object of this invention is to simplify and improve operating mechanism for dump car doors in a manner to meet the requirements for successful commercial use.

15 This invention is illustrated on the accompanying sheets of drawings, in which—

Figure 1 is a fragmentary side elevation of a dump car embodying my invention; and

20 Fig. 2 is a transverse sectional view of the same car, the section being taken in the plane of line 2—2 of Fig. 1.

The various novel features of the invention will be apparent from the following description and drawings, and will be particularly pointed out in the appended claims.

Referring to the figures of the drawings, it will be noted that I have shown a dump car, the body of which includes sides 10, ends 11, and a floor 12, which in this particular instance includes stationary A-shaped portions 13 and 14, the former being located at the ends of the car and over the trucks, including wheels 15, and the other stationary portion 14 of the floor being located intermediate the trucks and at a lower level than the portions 13. These floor portions 13 and 14 extend outwardly and downwardly from the center of the car, or substantially from the center of the car toward 40 the sides of the car.

To normally close the dumping opening between the sides 10 of the car and the lower edges of the stationary A-shaped portion 13, I have provided vertically swinging dump doors 16 which preferably are horizontally pivotally connected along the lower edges of the sides 10 of the car. Likewise, to normally close the dumping opening between the sides of the car and the lower edges of 50 the stationary floor portion 14, relatively larger intermediate vertically swinging dump doors 17 are provided which preferably are horizontally pivotally connected at their upper edges adjacent the lower

edges of the sides of the car, and extend 55 downwardly and inwardly toward the lower edges of the floor portion 14. As shown the pivotal connections for doors 17 are lower than the pivotal connections for the doors 16. In this case the larger intermediate 60 doors 17 are straight, and the smaller dump doors 16 over the trucks are angular in form, but it will be appreciated that these doors may be of any desired shape.

This invention has to do primarily with 65 the operating mechanism for these dump doors, the lower edges of which lie in different horizontal planes. This door operating mechanism includes an operating shaft 18 being carried by the relatively 70 small doors 16 located over the trucks, the shaft 18 preferably being continuous from one end of the car to the other, so that it extends not only the length of the doors 16, but also the distance therebetween, or in 75 other words, extends also the full length of the intermediate dump doors 17. It will be apparent, however, from the description to follow that this shaft need not extend the whole length of the intermediate doors 17, 80 but may be a split shaft or a plurality of shaft sections having merely an overlapping relationship therewith, in the event that it is desired to operate less than all of the doors on the same side of the car at a time or 85 during a single operation. This operating shaft 18 is provided with one or more arms 19 fixed thereon, the free end of each of which is pivotally connected to one end of an intermediate link 20, the other end of 90 which is pivotally connected to one end of a lock or hooked member 21, the opposite end of which is pivoted at 22 to a fixed portion of the car frame, the function of the hooked member 21 being to lock the dump 95 doors 16 over the trucks in closed position, as shown at the left hand side of Fig. 2. A similar lock or hooked member 23 in each case is pivotally connected at 24 to a fixed portion of the car frame, and has for its 100 function the locking of the associated intermediate dump door 17. It will be noted in each case that the lower lock member 23 hooks over a projection 25 at the lower end of the associated intermediate dump door 105 17 to hold said door in locked position, and that the upper lock member 21 hooks over the shaft 18 for holding the dump doors

16 over the trucks in closed position. The lock members 21 and 23 are connected by a link 26 whereby their operation, or in other words, their locking and unlocking movements may be simultaneous.

Referring more particularly to the left hand side of Fig. 2, it will be noted that the dump doors 16 and 17, the lower edges of which coöperate with angle portions at the outer edges of the floor portions 13 and 14 to form a tight seal, are in their closed positions, in which positions said doors are locked by the locking members 21 being hooked over the operating shaft 18 and the locking members 23 being hooked over the door projections 25. At this point it will be noted also that the operating shaft 18 positively engages and presses the intermediate dump door 17 toward a closed position. If now, it is desired to open the dump doors 16 and 17, the same is accomplished by rotating the operating shaft 18 in a direction to force its relatively fixed arm or arms 19 outwardly and upwardly, the first movement of which causes the locking members 21 and 23 to be raised out of a locking position, whereupon the dump doors 16 and 17 are free to open. In this connection it will be appreciated that the material in the car to be dumped will assist in a further opening movement of the doors. Assuming, however, that there is no material in the car to be dumped, a further rotation of the shaft 18 in the same direction will cause the shaft to move bodily outwardly from under the link 20 and out of engagement with the intermediate dump door 17 into the position shown at the right hand side of Fig. 2, wherein the dump doors 16 over the trucks are in an open position for permitting a dumping action, and the intermediate door 17 also in a position to permit a dumping action, the intermediate dump door 17 being independent in this position of the other dump doors 16 and of the operating shaft 18.

In closing the dump doors 16 and 17 from an open position, as shown on the right hand side of Fig. 2, the shaft 18 is rotated in a manner to cause its fixed arm or arms 19 to rotate upwardly and outwardly, whereupon the dump doors 16 over the trucks will be given a closing movement, it being understood that the operating shaft 18 under these conditions approaches the intermediate dump door 17. During this closing movement, when the shaft 18 passes into engagement with the intermediate dump door 17, it will cause the latter also to take a closing movement, it being understood that during this operation the shaft 18 is rolling itself under the link 20 and under the locking member 21. Finally, the doors 17 with doors 16 are forced into a closed position, the last portion of the rotary movement of the operating shaft 18 causing the members

21 and 23 to swing downwardly into a locking position for holding the dump doors in such closed position.

It will be understood that any number of arms 19, links 20, locking members 21 and 23, and links 26 may be provided along the length of the car, and that the equipment on both sides of the car is the same.

It is my intention to cover all modifications of the invention falling within the spirit and scope of the following claims.

I claim:

1. A car of the class described provided with a plurality of vertically swinging doors pivoted at the outer sides of the car, some of the doors having their swinging edges in different horizontal planes from other associated doors, and means for actuating the doors by one operation, the actuation of one of said doors being dependent upon the actuation of another one of said doors.

2. A car of the class described provided with a plurality of vertically swinging doors pivoted at the outer sides of the car, some of the doors having their swinging edges in different horizontal planes from other associated doors, and means for closing the doors by one operation, the closing of one of said doors being dependent upon the closing of another one of said doors.

3. A car of the class described provided with a plurality of vertically swinging doors pivoted at the outer sides of the car, some of the doors having their swinging edges in different horizontal planes from other associated doors, and means for closing and locking all of the doors by one operation, the closing of one of said doors being dependent upon the closing of another one of said doors.

4. A car of the class described provided with a plurality of vertically swinging doors pivoted at the outer sides of the car, some of the doors having their swinging edges in different horizontal planes from other associated doors, and means for unlocking and opening all of the doors by one operation, the opening movement of one of said doors being dependent upon the opening of another one of said doors.

5. A car of the class described provided with a plurality of outwardly swinging side dump doors, some of the doors having their swinging edges in different horizontal planes from other associated doors, and means for actuating and changing the locking condition of the doors by one operation, the actuation of one of said doors being dependent upon the actuation of another one of said doors.

6. In a dump car, the combination of a plurality of doors, and a shaft carried by one of said doors and movable into engagement with another of said doors for actuating the latter.

95

105

115

125

130

7. In a dump car, the combination of a plurality of dump doors, a shaft carried by one of said doors and movable into engagement with another one of said doors for giving the latter a closing movement. 5

8. In a dump car, the combination of a plurality of doors, an operating shaft therefor, and inter-connected locking hook members for said doors, one of said hook members being connected to said shaft through the other hook member. 10

9. In a dump car, the combination of a plurality of doors, inter-connected locking hook members for said doors, and an operating shaft carried by one of said doors for actuating said locking members. 15

10. In a dump car, the combination of a plurality of doors, inter-connected hook locking members for said doors, an operating shaft carried by one of said doors, and an operative connection between said operating shaft and one of said locking members for controlling the position of said doors. 20

11. In a dump car, the combination of a plurality of doors, inter-connected hook locking members for said doors, an operating shaft carried by one of said doors, an arm rigidly connected to said operating shaft, and an operative connection between said arm and one of said locking members whereby the movement of said doors is controlled and whereby the locking condition of said doors also is controlled. 25

12. In a dump car, the combination of a plurality of doors the lower edges of which are in different horizontal planes, a locking member for the lower edges of each of said doors, a connection between said locking members whereby they may be actuated simultaneously, and an operating shaft operatively connected to said locking members through the actuation of which the locking condition of said doors is controlled. 30

13. In a dump car, the combination of a plurality of doors the lower edges of which are in different horizontal planes, a locking member for the lower edges of each of said doors, a connection between said locking members whereby the same are simultaneously operated, and an operating shaft carried by one of said doors and operatively connected to said locking members for actuating the latter, said operating shaft at times engaging another one of said doors for controlling its movement. 45

14. In a dump car, the combination of a plurality of pivotally mounted dump doors, an operating shaft carried by one of said dump doors, a pivotally mounted locking member engaging said shaft for locking the doors in closed position, a link connection between said locking member and said shaft whereby the doors may be actuated, another pivotally mounted locking member for locking another one of said doors in closed position, 50

and a connection between said locking members whereby the locking and unlocking action thereof will be simultaneous. 55

15. In a dump car, the combination of a plurality of pivotally mounted dump doors, 70 an operating shaft carried by one of said doors and movable into engagement with another of said doors for pressing the latter into closed position, a pivotally mounted locking member which in one position hooks over the shaft for locking one of said doors in closed position, an arm rigidly connected to said operating shaft and having a link connection with said locking member for transmitting movement to said doors, 80 another pivotally connected locking member for locking another one of said doors in closed position, and an operating connection between said locking members whereby the same may be actuated by one operation. 85

16. In a dump car, the combination of a plurality of vertically swinging dump doors having their horizontal pivotal mountings in different horizontal planes, an operating shaft carried by one of said doors and movable into engagement with another of said doors for transmitting a closing movement thereto, a pivotally mounted locking member which in one position hooks over the shaft for locking one of said doors in closed position and holding another one of said doors in closed position, another pivotally mounted locking member for holding said other door in closed position, an operative connection between said locking members, an arm rigidly connected to said operating shaft having a link connection with one of said locking members whereby the doors may have their locking conditions changed and operated by one operation. 95

17. A dump car provided with a plurality of swinging doors, and means mounted upon one of said doors for engaging the adjacent door whereby the latter door is closed by the operation of the former door. 100

18. A dump car provided with a plurality of swinging doors, an operating member mounted upon one of said doors, and means for bringing said operating member into engagement with an adjacent door by the 115 operation of the said member.

19. A dump car provided with a plurality of swinging doors having their swinging edges in different horizontal planes, a plurality of locking members mounted upon a 120 stationary part of the car, a connection between said locking members, and means connecting one of said locking members with one of the doors, whereby said locking members are simultaneously operated by the operation of the door. 125

20. A dump car provided with a plurality of swinging doors having their lower edges in different horizontal planes, a plurality of locking members attached to a stationary 130

part of the car for engaging said doors at or near their lower edges, and means for operating said locking members.

21. A dump car provided with a plurality of swinging doors having their lower edges in different horizontal planes, a plurality of locking members attached to a stationary

part of the car for engaging said doors at or near their lower edges, and means for simultaneously operating said locking members.

Signed at Chicago, Illinois, this 14th day of September, 1918.

HARRY S. HART.
